(57) **CLAIM**

The ornamental design for a fan cover for a convection oven, as shown and described.

DESCRIPTION

FIG. 1 is a front perspective view of a fan cover for a convection oven showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The even-length broken lines showing portions of the fan cover are included for the purpose of illustrating environmental structure and form no part of the claimed design. The uneven-length broken lines define the bounds of the claimed design and form no part thereof.
